UNITED STATES PATENT OFFICE.

FRANK W. YOUNG, OF PROVIDENCE, RHODE ISLAND.

CUFF-LINK.

1,156,651.

Specification of Letters Patent. Patented Oct. 12, 1915.

Application filed March 24, 1915. Serial No. 16,595.

To all whom it may concern:

Be it known that I, FRANK W. YOUNG, a citizen of the United States, and resident of the city of Providence, in the county of Providence and State of Rhode Island, have invented certain new and useful Improvements in Cuff-Links, of which the following is a specification.

This invention relates to cuff links or fasteners and has for its object to provide a yoke member of resilient material folded to embrace the outside of the cuff, the yoke being provided with inwardly extending buttons or engaging members to pass 15 through the cuff button-holes.

A further object of the invention is to rivet the button heads or engaging members into the ends of the yoke and to fold these ends inwardly and back over nearly upon 20 themselves, whereby the button heads extend inward toward each other and the riveted ends are covered by the fold.

A further object of the invention is to extend these button heads or engaging members inwardly nearly in contact with each other, whereby the yoke arms are caused to 25 spring apart to permit the cuff fabric to pass therebetween, in positioning the holder on the cuff by which construction it is impossible for the holder to become inadvertently 30 disengaged from the cuff even when the cuff is made of soft or unstarched material such as silk or the like.

Another feature of this invention is the 35 folding of the middle portion of the yoke inwardly a short distance at the bend forming pockets or grooves into which the front edges of the cuff extend and by which these edges are held firmly in the desired position and in spaced apart relation.

With these and other objects in view, the invention consists of certain novel features of construction, as will be more fully described, and particularly pointed out in the 45 appended claim.

In the accompanying drawings: Figure 1— is a perspective view showing my improved holder applied to a cuff. Fig. 2— is a perspective view showing the strip of metal 50 from which my improved yoke member is formed, also showing the openings punched therein for the reception of the lugs on the button shank to be riveted therein. Fig. 3— illustrates one of the button or button-hole 55 engaging members showing the lugs on the shank portion adapted to be riveted to the

yoke. Fig. 4— shows the button shanks as riveted to the ends of the metal strip before the latter is bent into yoke form. Fig. 5— is a side view of the finished yoke showing 60 the same as being in substantially the form of the letter W with the ends of its extending side arms folded inwardly upon themselves. Fig. 6— shows a portion of the doubled fabric of a folded cuff in section with my 35 improved holder attached thereto.

My improved yoke member is preferably constructed from a strip of resilient or spring stock, usually from the precious metals or from metals plated with the same. 70 This strip may be cut in any desired ornamental form, but I have illustrated the same as of the plainest design. This strip is folded into substantially the shape of the letter W, the side arms 15 and 16 being set on a slight angle to each other, and the middle portion 10 at the bend is folded inwardly a short distance forming pockets or grooves 11 and 12 on either side into which the front edges of the cuff extend and by which these 80 edges are retained firmly in spaced apart relation. The elongated side arms of the yoke are arranged to extend along and embrace the outside portions of the cuff, and in the end portions 17 and 18 of these side arms are 85 formed eyes 19 into which the lugs 20 of the button shank 21 are set and riveted. The outer end of this shank may be formed into any desired shape but the ordinary button 90 or bean head is herein shown. The end portions of these side arms are folded inwardly and back upon themselves, thereby completely covering or hiding from view the riveted or swaged ends of the button shank lugs. By this construction of folding the 95 ends backward upon themselves a number of advantages are gained; first, a button is adapted to be riveted into place and the riveted portions neatly hidden from view, otherwise I would be obliged to connect the 100 buttons to the arms by soldering and as is well known in the art the application of heat necessary for soldering to plated metal injures the plate and the heat also removes the temper from the spring stock.

Another feature of my improved cuff link is that the button portions extend inwardly toward each other to nearly meet, whereby it is necessary to spring these members apart slightly in order to pass the fabric of the 110 cuff between them in positioning the yoke on the cuff and by this construction, it will

be seen that the finest and softest fabric cannot become accidentally disengaged from the button heads. The yoke is very readily positioned upon the cuff and when in position holds the cuff firmly in the desired shape.

I claim:

A cuff retainer comprising a substantially W shaped resilient yoke member adapted to engage and retain the individual edges of the cuff in spaced apart relation the elongated side arms of the yoke being adapted to extend along and embrace the opposite outside portions of the cuff, the ends of said

arms being folded back upon themselves, and button-hole engaging members fixed to said inturned ends and extending inward toward each other, the inner ends of said members nearly contacting, whereby the yoke arms are caused to spring apart to permit the cuff fabric to pass between in positioning said yoke on the cuff.

In testimony whereof I affix my signature in presence of two witnesses.

FRANK W. YOUNG.
